UNITED STATES PATENT OFFICE

PAUL V. BENEVILLE, OF DUMONT, NEW JERSEY, ASSIGNOR TO BIGELOW SANFORD
CARPET CO., INC., A CORPORATION OF MASSACHUSETTS

DESIGN FOR A CARPET

Application filed November 4, 1932. Serial No. 45,765. Term of patent 7 years.

To all whom it may concern:

Be it known that I, PAUL V. BENEVILLE, a citizen of the United States, and resident of Dumont, in Bergen County and State of New Jersey, have invented a new, original, and ornamental Design for a Carpet, of which the following is a specification, reference is had to the accompanying drawing, forming part thereof in which a plan view of the carpet is shown.

The dot and dash lines define the unit of the design. The upper right hand corner of the unit designated "A" is repeated at the unit designated "B", mid-way the left hand vertical edge of said unit, while the lower left hand corner of the unit designated "D", is repeated at the point designated "C", mid-way the right hand vertical edge.

I claim:

The ornamental design for a carpet substantially as shown and described.

PAUL V. BENEVILLE.
